(57) CLAIM

The ornamental design of a hand-held monitor, as shown and described.

DESCRIPTION

FIG. 1 is a perspective view of an embodiment of a hand-held monitor;

FIG. 2 is a top plan view of the embodiment of FIG. 1; FIG. 3 is a bottom plan view of the embodiment of FIG. 1; FIG. 4 is a front elevational view of the embodiment of FIG. 1;

FIG. 5 is a right side elevational view of the embodiment of FIG. 1;

FIG. 6 is a back elevational view of the embodiment of FIG. 1; and,

FIG. 7 is a left side elevational view of the embodiment of FIG. 1.

The portion of the article shown in broken lines throughout the views is for illustrative purposes only and forms no part of the claimed design.
